United States Patent Office

Des. 181,376
Patented Nov. 5, 1957

181,376

FIRE ALARM

Robert G. Smith, Bronxville, N. Y., assignor to Merlite Industries, Inc., New York, N. Y., a corporation of New York

Application October 2, 1956, Serial No. 43,178

Term of patent 14 years

(Cl. D72—1)

FIG. 4

FIG. 3

FIG. 2

FIG. 1

Fig. 1 is a front elevation of a fire alarm showing my new design;

Fig. 2 is a side elevation of the same;

Fig. 3 is a plan view of the same looking downwards, and

Fig. 4 is a plan view of the same looking upwards.

I claim:

The ornamental design for a fire alarm, as shown.
